M. M. MARCUSE.
LIQUID DISPENSING DEVICE.
APPLICATION FILED JAN. 7, 1911.

1,073,864.

Patented Sept. 23, 1913.

2 SHEETS—SHEET 2.

UNITED STATES PATENT OFFICE.

MOSES M. MARCUSE, OF NEW YORK, N. Y., ASSIGNOR TO WEST DISINFECTING COMPANY, OF NEW YORK, N. Y., A CORPORATION OF NEW YORK.

LIQUID-DISPENSING DEVICE.

1,073,864.

Specification of Letters Patent. Patented Sept. 23, 1913.

Application filed January 7, 1911. Serial No. 001,447.

To all whom it may concern:

Be it known that I, Moses M. MARCUSE, a citizen of the United States, and resident of the borough of Manhattan, in the city and State of New York, have invented a new and useful Improvement in Liquid-Dispensing Devices, of which the following is a specification.

This invention relates to certain improvements in the construction, form and arrangement of the several parts of a liquid dispensing device which is particularly well adapted for dispensing liquid soap or other liquid cleansing or antiseptic substance, into the hands of the person using the same.

This invention includes a novel construction and arrangement of the liquid ejecting plunger for the dispensing vessel.

In the accompanying drawings, Figure 1 is a top plan view of the liquid dispensing device, Fig. 2 is a front view of the same, Fig. 3 is a side view, the vessel being shown in an inverted position in dotted lines, Fig. 4 is a detail section showing the concealing screw for fastening the meeting ends of the vessel supporting band together, Fig. 5 is a vertical central section through the device, Fig. 6 is a partial side view, portions of the parts being broken away and the special tool being shown in connection therewith in position for removing the dispensing nozzle, Fig. 7 is a view partly in side elevation and partly in section, showing the vessel in its inverted position, and Fig. 8 is an inverted plan view partly in section, of the special tool used in connection with the device.

The bracket for supporting the liquid dispensing vessel comprises a post 1, its base 2 and head 3, from which head extend the bracket arms 4 and 5. These bracket arms may occupy any desired angular position with respect to the post 1. In the present instance, the post is shown as extended horizontally and the arms as depending vertically therefrom.

The vessel 6 may be made of any desired shape and material, preferably approximately globular and of glass. The upper continuous bead 7 and the lower interrupted bead 8 surround the vessel 6, between which beads is located the split supporting band 9 which embraces the vessel 6. The meeting ends of this band 9 are provided with ears 10, 11, having alined holes 12, 13, in which

is located a concealed screw 14 for fastening the ends of the band together snugly around the vessel 6. At the front of the vessel, the band 9 is provided with a tilting handle 15 formed integral therewith. This supporting band 9 is further provided at its sides with pivots 16, 17, formed integral therewith, which pivots are forced into suitable sockets in the ends of the bracket arms 4, 5, for pivoting the vessel to the said bracket. The pivot 17 at one side of the band 9 is provided with a disk segment 18 formed integral therewith, which segment forms a stop for limiting the tilting movement of the vessel.

Means are provided for tilting the vessel 70 by the foot, if so desired, as follows: The disk segment 18 is provided with a lug 19, to which one end of a link 20 is pivoted, the other end of which link is attached to the upper end of a wire, chain, rod or other connection 21, the lower end of which is attached to a foot treadle 22. A spring 23 serves to hold the foot treadle 22 in its raised position, and where the connection 21 is a rod, this spring 23 also serves to remove the weight of the rod 21 and link 20 from the vessel 6.

The mouth 24 of the vessel 6, is closed by a cap 25 permanently secured around the outer wall of said mouth. This cap 25 is 85 provided with an interiorly screw-threaded lug 26, into which is screwed the dispensing nozzle 28. The liquid ejecting plunger 27, 27* is mounted upon a U-shaped wire guide 29, 29* in position to enter the nozzle 28 90 when the vessel is inverted, for discharging the liquid from within said nozzle. In the present instance, the wire guide has the upper end of its longer branch 29 soldered or otherwise secured to the cap 25 and its 95 shorter branch 29* extended upwardly into the interior of the plunger 27. One method of attaching the plunger to the guide so that the plunger will be attached thereto against removal, is to divide the plunger into two 100 separable members, the lower member 27* being first placed onto the branch 29* of the guide, after which a ball 29** is screwed or otherwise secured to the upper end of the branch 29*. The upper member 27 of 105 the plunger is then secured to the lower member. The hole at the bottom of the inner member 27 is smaller than the bore in

the plunger and smaller than the ball 29**, so that the plunger may have a free sliding movement without danger of becoming detached from its guide. The short branch 5 of the wire guide for the plunger is arranged at such an angle to the vertical axis of the vessel that the plunger will not begin to slide for ejecting liquid from the interior of the nozzle 28, until the vessel has nearly reached the limit of its inverted movement. 10 This insures the accurate ejection of the liquid even when there is very little left in the vessel.

An air vent tube 31 extends inwardly 15 from the cap 25, through the mouth 24, into the interior of the vessel 6, for insuring a freer dispensing of the liquid when the vessel is inverted.

Means are provided for locking the vessel 20 against being tilted, which means comprise a concealed screw 32 in the head 3 of the post 1 of the bracket, the point of which screw is arranged to enter the discharge opening 30 of the dispensing nozzle 28.

25 Means are provided for preventing the unscrewing of the nozzle 28 by an ordinary tool, which means comprises a sleeve 33 surrounding the exposed portion of the nozzle 28, said sleeve being held in position on the 30 shank of the nozzle by a nut 34 having a shouldered engagement with the sleeve and a screw-threaded engagement with the said shank, said nut being interposed between said sleeve and shank. The arrangement of the parts is such that the sleeve 33 is held in such a position that it may freely rotate 35 around said nozzle without turning the nozzle, and the diameter of the sleeve is slightly greater than the diameter of the head of the 40 nozzle, so as to prevent the grasping of the nozzle by a wrench or other ordinary tool.

Means are provided for concealing the screws 35 which fasten the base 2 of the post 1 of the bracket to the wall or other support, which means comprises a disk 36 and a collar 37 slidably mounted on the post 1. A concealed screw 38 engages the collar 37 and post 1 for locking the collar and disk in their protective position. To insure the 50 screw holes in the collar 37 and post 1 being brought into alignment for the introduction of the screw 38, the collar 37 is provided with a centering pin 39 which enters a hole in the face of the base 2.

55 A series of special tools may be provided for use in connection with the liquid dispensing device, but in the present instance a special tool, illustrated in Figs. 6 and 7, is provided, which tool has a socket wrench 40 at one end arranged to turn the screws 32 and 38, and a screw-driver 41 at its other end arranged to turn the screw 14. This tool is further provided with a socket 42 intermediate its ends, which socket is provided with spanner lugs 43, 44, arranged to

enter the discharge opening 30 and the spanner hole 45, respectively, in the head of the nozzle.

A device constructed and arranged substantially as herein set forth will be amply 70 protected from being tampered with by any unauthorized persons. Furthermore, the construction is materially improved and the dispensing of the liquid facilitated.

The feature of the means for locking the 75 liquid dispensing vessel against movement shown and described but not claimed herein, forms the subject matter of a divisional application filed by me the 24th day of June, 1911, Serial No. 635178.

The feature of the means for preventing the removal of the dispensing nozzle by an ordinary tool shown and described but not claimed herein, forms the subject matter of a divisional application filed by me the 13th 85 day of May, 1913, Serial No. 767288.

It is obvious that various changes might be resorted to in the construction, form and arrangement of the various parts without departing from the spirit and scope of my 90 invention; hence I do not wish to limit myself strictly to the structure herein set forth, but

What I claim is:

1. A bracket, a liquid dispensing vessel 95 pivoted thereto, a nozzle, a weighted plunger for positively ejecting the liquid through the nozzle when the vessel is inverted, and a wire guide having a branch extended into the plunger for slidably supporting it in 100 position.

2. A bracket, a liquid dispensing vessel pivoted thereto, a nozzle, a weighted plunger for positively ejecting the liquid through the nozzle when the vessel is inverted, and a wire guide having a branch extended into the plunger for slidably supporting it in 105 position and means for retaining the plunger on said branch.

3. A bracket, a liquid dispensing vessel 110 pivoted thereto, a nozzle, a weighted plunger for positively ejecting the liquid through the nozzle when the vessel is inverted and a U-shaped wire guide having a longer branch attached to the vessel and a shorter branch 115 extended into the plunger for slidably supporting the plunger.

4. A bracket, a liquid dispensing vessel pivoted thereto, a cap secured to the mouth of the vessel, a nozzle carried by said cap, 120 a weighted plunger for positively ejecting the liquid through the nozzle when the vessel is inverted and a U-shaped guide having a longer branch attached to the cap and a shorter branch extended into the plunger 125 for slidably supporting the plunger.

5. A bracket, a liquid dispensing vessel pivoted thereto, a nozzle, a weighted plunger for positively ejecting the liquid through the nozzle when the vessel is inverted and 130

a guide for the plunger arranged at such an angle to the vertical axis of the vessel that the plunger will not start on its ejecting movement until the vessel has nearly reached the limit of its inverted movement.

In testimony, that I claim the foregoing as my invention, I have signed my name in

presence of two witnesses, this sixth day of January, 1911.

MOSES M. MARCUSE.
